ATTORNEYS,

Patented Dec. 23, 1924.

UNITED STATES PATENT OFFICE.

ARTHUR J. TIZLEY, OF BROOKLYN, NEW YORK, ASSIGNOR TO THE BRYANT ELECTRIC COMPANY, OF BRIDGEPORT, CONNECTICUT, A CORPORATION OF CONNECTICUT.

CANDLE SOCKET.

Application filed January 18, 1923. Serial No. 613,423.

To all whom it may concern:

Be it known that I, ARTHUR J. TIZLEY, a citizen of the United States of America, residing in the city of New York, borough of Brooklyn, county of Kings, and State of New York, have invented certain new and useful Improvements in Candle Sockets, of which the following is a specification.

My invention relates to candle sockets, and particularly to the supporting standard for the lamp receptacle in a socket of this type. The object of my invention is to provide a rugged standard which may be economically manufactured, easily installed, and readily adjusted to candle casing of different length.

In the accompanying drawings—

Fig. 1 is a vertical section through a candle socket in which my invention is embodied in one form;

Fig. 2 is a perspective of the standard alone; and

Fig. 3 is a perspective of a modified construction of one end of the standard.

In fittings of the present type, the lamp receptacle 5 is spaced from the wire conduit 6 by a standard of some type in order to present the lamp (not shown) in proper position at the upper end of the candle-like casing 7 supported in any suitable fashion—e. g., on a cup 8 secured at the end of the wire conduit 6. In its general features the construction shown is of usual type, and the present invention relates solely to the standard which has certain features of advantage over those commonly in use.

As shown, the standard comprises a pair of telescoping brackets 9 and 10, adapted respectively for connection to the wire conduit 6 on the one hand, and to the lamp receptacle 5 on the other hand. Both bracket elements are struck from sheet metal and formed to shape. The bracket 9 comprises a pair of arms *a* and *b*, the webs of which are integral with and offset in the same direction from the base 11. The latter carries a bushing 12 adapted to screw on the threaded end 13 of the conduit 6 and to clamp the bottom of the cup 8 against the nut 14. A set screw 15 piercing the nipple may be provided to secure the bracket in fixed position on the conduit. The bracket arms are longitudinally slotted at 16 to afford outlets for the wires 17 and 18, which may thus be freely led to the binding screws

19 and 20 on the socket 5. At their free ends the arms of the bracket 9 form jaws to guide and grip the arms of the bracket 10. For this purpose the ends of the webs are offset to form end flanges 21. Lateral guide wings 22 at the sides of the arms are spaced sufficiently from the ends of the flanges 21 to form channels in which are received the edges of the arms *c* and *d* of the bracket 10, the webs of which lie at right angles to the planes of the webs *a*—*b* of bracket 9. A clamping screw 23 passes freely through the web *a* of the bracket 9 and takes into a tapped hole in the web *b*. The jaw formed by the free ends of the arms of bracket 9 may be thus forced into gripping engagement with the edges of the webs *c* and *d* of bracket 10, and thus secure the parts together rigidly in adjusted position.

At the head of the bracket 10 is a screw nipple 24 which may be economically formed from the metal of the bracket 25 by a drawing and threading operation. The nipple 24 takes into a cooperating nipple 27 carried by a hickey 26 on the base of the receptacle 5 in the construction shown in Fig. 1.

In the modification shown in Fig. 3 the hickey 26 is dispensed with, and attaching lugs 28 are struck from the webs *c* and *d* of the bracket 10 and offset to a position in extension of the head 25 of the bracket. The lugs are pierced at 29 and tapped to receive the screw bolts 30, which in Fig. 1 serve to secure the hickey to the base of the receptacle.

The operation of the device is readily understood. In order to adjust the length of the standard to the length of the candle casing 7, the screw 23 is retracted sufficiently to release the grip on the arms *c* and *d* of bracket 10. The latter may be then adjusted telescopically to desired position, and the screw 23 again tightened to force the jaw of bracket 9 into gripping engagement with the edges of webs *c* and *d* of bracket 10. The flanges 21 and the guide wings 22 of the jaw serve to maintain the webs of the bracket 10 uniformly spaced, and insure their rectilinear movement with respect to the webs of the bracket 9. The standard is readily secured to the threaded end of the wire conduit 6 by means of a screw nipple 12, and to the socket by means of a nipple 24, or the supporting arms 27. The line

wires are readily carried up through the standard and may be passed through the nipple 24, when the latter is used, or through the openings 16 in the bracket 9, or through the openings between the spaced sides of the bracket 10, when the latter stands sufficiently above the bracket 9 to permit the exit of the wires at this point. The rectangular structure of the standard secures an exceptional rigidity of support for the lamp receptacle, while at the same time the device is readily and cheaply manufactured and convenient in service. The wires are always readily accessible and may be drawn from the standard in any one of the several ways mentioned.

Various modifications in detail of construction will readily occur to those skilled in the art, without departing from what I claim as my invention.

I claim—

1. A socket-supporting standard comprising a pair of double-armed brackets in sliding engagement at their adjacent ends, and having their webs lying in spaced planes at right angles to each other, means for forcing the arms of one of said brackets into gripping engagement with the arms of the

other bracket, means on one of said brackets for mounting the standard on a conduit end, and means on the other bracket for securing the same to a lamp receptacle element.

2. A socket-supporting standard comprising a pair of double-armed brackets in sliding engagement at their adjacent ends, and having their webs lying in spaced planes at right angles to each other, means for forcing the arms of one of said brackets into gripping engagement with the arms of the other bracket, interengaging elements maintaining said ends in determined slidable relationship to each other, means on one of said brackets for mounting the standard on a conduit end, and means on the other bracket for securing the same to a lamp receptacle element.

3. In a supporting standard for candle sockets, a bracket element having a base and upstanding opposed arms integral therewith, flanges offset toward each other from the ends of the arms, and lateral wings on said arms coacting with said end flanges to form guide ways.

In testimony whereof I have signed my name to this specification.

ARTHUR J. TIZLEY.
